No. 775,196.

PATENTED NOV. 15, 1904.

F. C. SOMES.

MECHANICAL COKE PULLER.

APPLICATION FILED APR. 7, 1904.

NO MODEL.

UNITED STATES PATENT OFFICE.

FRANK CHASE SOMES, OF WASHINGTON, DISTRICT OF COLUMBIA,
ASSIGNOR TO JAMES ELLWOOD JONES, OF SWITCHBACK, WEST
VIRGINIA.

MECHANICAL COKE-PULLER.

SPECIFICATION forming part of Letters Patent No. 775,196, dated November 15, 1904.

Application filed April 7, 1904. Serial No. 202,047. (No model.)

To all whom it may concern:

Be it known that I, FRANK CHASE SOMES, a citizen of the United States of America, and a resident of Washington, in the District of Columbia, have invented certain new and useful Improvements in Mechanical Coke-Pullers, of which the following is a specification.

This invention relates to a coke-puller designed to be operated by machine for pulling coke from coke-ovens, and it is particularly adapted for discharging beehive coke-ovens. In the manufacture of metallurgical coke the oven known as the "beehive" oven, so called because of its dome-shaped form, has been generally adopted, being found to give the best results. In the burning and wetting of the coal the coke is produced in a caked mass having a vertical stratification or columnar crystallization, and it is desirable to avoid as far as possible breakage of the sticks extracted from the oven.

The object of the invention is to secure a quick and thorough discharge of the oven without unnecessary breakage of the coke.

The invention relates more particularly to an underworking wedge-like scraper movable over the bottom of the coke-oven and operative on its instroke to loosen the coke for withdrawal and on its outstroke to withdraw the so-loosened coke.

The invention consists principally in the combination, with the underworking wedge-like scraper operating to loosen the caked coke on the instroke and withdraw the loosened coke on the outstroke, of a sliding extension operative on the outstroke to withdraw the loosened coke directly over the scraper at the inner end of its stroke or coke which may fall over the scraper during the outstroke.

Figure 1 of the accompanying drawings represents a plan view, partly in section, of one form of this invention. Fig. 2 represents a longitudinal vertical section thereof on line 2 of Fig. 1, showing the coke-puller on its instroke operating to loosen the coke within the oven. Fig. 3 represents a similar section showing the coke-puller on its outstroke and the extension in operation. Fig. 4 represents

a transverse section of the coke-puller bar on line 4 4 of Fig. 2.

The same reference characters indicate corresponding parts in all the figures.

This coke-puller is designed to be mounted on a machine adapted to thrust it into and retract it from the oven and swing it laterally in either direction to enable it to engage the coke at the sides of the oven. The machine shown in the expired United States Patent No. 446,936 may be used for this purpose. The coke-puller comprises an actuating-bar 10, which is preferably rigid throughout, the rear portion thereof having a rack-bar or rack-teeth 11 corresponding to the rack-bar 'a' of said patent and the front portion having a longitudinal socket 12 and a longitudinal passage 13 connecting said socket with the outer end of the bar. A scraper 20 is disposed at the front end of the bar 10. This scraper, which is hollow or otherwise, is of wedge-like form and of a breadth equal to the desired width of the scraper, and it comprises when hollow two opposite side plates 21 and 22, an inclined top plate 23, and an upright or approximately upright plate 24. These plates are made of thick metal or of refractory material adapted to withstand the heat of the oven. The body of the scraper may be provided when hollow with longitudinal partitions, as 25 and 26, having rounded projections, as 27 and 28, on their lower edges, adapted to slide over the oven-bottom on the in and out stroke of the coke-puller. This scraper may be of any suitable form whereby it is adapted to perform the double function of loosening and withdrawing coke.

A sliding extension 30 serves to extend the coke-puller on the outstroke to receive coke which may have rested on or may fall over the inclined front of the scraper. This sliding extension may be in the form of a solid or skeleton plate disposed underneath the scraper and adapted to slide forward to extend the coke-puller or permit the scraper to move backward over it. This sliding extension-plate 30 is provided with a shank 31, which extends through the passage 13 into the socket 12 of the bar 10 and is provided

at its inner end with a head 32. An expansive spring 40 is disposed in the socket 12, between the inner end thereof and the head 32 of the shank of the sliding extension-plate, and 5 operates normally to thrust said plate forward and hold it in extended position. The front end of the bar 31 is provided with a lateral attaching-lug 33, which forms connection with the sliding plate. This lug is 10 adapted to form a stop for the sliding extension at its inner and outer positions and is adapted to be engaged by the front portion of the scraper on the outward stroke thereof from the oven, whereby the extension in 15 open position is drawn out with the scraper. In the use of this invention the coke-puller is thrust into the oven, along the bottom thereof, a sufficient distance to make a proper drawing of coke. On this stroke the extension 20 comes in contact with the coke, and the resistance thereof tends to close said extension under the scraper, as shown in Fig. 2, the tension of the spring 40 being preferably such as to permit such closing; but the upper 25 beveled front face of the scraper operates like a wedge to lift the coke under which it passes and to loosen such coke from the caked mass of coke within the oven. The main portion of the so-loosened coke falls behind the 30 scraper; but at the end of the stroke a small part thereof lies over the top of the scraper. The outstroke of the coke-puller for the withdrawal of the coke is then made, and the scraper 20 moves outward over the extension-plate 35 30, which is held stationary by the spring 40 until the lug 33 engages the rear bar of said plate. The back 24 of the scraper pulls out the main body of the loosened coke; but the coke which was immediately above the scraper 40 at the end of the stroke falls forward in front of the scraper and is caught on the extension-plate 30, as shown in Fig. 3, and withdrawn from the oven. When an stroke is made to the far side of the oven, if the extension-plate is not closed by the resistance 45 of the coke the front end of said plate comes in contact with the wall of the oven, and the forward motion of the coke-puller causes the spring 40 to be contracted and the scraper to 50 slide over said plate up against the oven-wall, so as to loosen the caked coke adjacent thereto. At the beginning of the outstroke from this point the sliding extension 30 is held against the oven-wall by the spring 40, and 55 the scraper 20 moves back over said plate and exposes it to receive coke which may fall forward from the scraper. As the lugs 27 or 28 or other projections at the front part of the scraper reach and engage the rear bar or part 60 of the extension-plate 30 the latter is retracted while in open position in unison with the outward movement of the scraper, and the coke which was directly above the scraper at the

end of the stroke and any that falls forward over the scraper on the outstroke is caught 65 on the extension 30 and is taken out thereby.

I claim as my invention—

1. A coke-puller comprising an underworking scraper adapted to operate on its stroke to loosen coke for withdrawal and on its outstroke to withdraw loosened coke, and a sliding extension-plate movable on said scraper and adapted to receive and hold the loosened coke which falls thereon on the outstroke. 70

2. A coke-puller comprising an underworking wedge-like scraper adapted to operate on its stroke to loosen coke for withdrawal and on its outstroke to withdraw loosened coke, a sliding extension-plate at the bottom of said scraper, and means for extending said plate 80 to receive coke falling from said scraper on the outstroke. 75

3. A coke-puller comprising an underworking wedge-like scraper adapted to operate on its stroke to loosen coke for withdrawal and 85 on its outstroke to withdraw loosened coke, a sliding extension-plate at the bottom of said scraper, and automatic means for extending said plate to receive coke falling from said scraper on the outstroke. 90

4. A coke-puller comprising an underworking scraper operative on its stroke to loosen coke for withdrawal and on its outstroke to withdraw loosened coke, a sliding extension-plate supported underneath said scraper, and 95 means connected with said scraper for engaging said sliding extension-plate on the outstroke.

5. A coke-puller comprising an underworking scraper operative on its stroke to loosen coke for withdrawal and on its outstroke to withdraw loosened coke, a sliding extension-plate supported underneath said scraper, means connected with said scraper for engaging 100 said sliding extension-plate on the outstroke, and means for holding said plate stationary during a portion of the outward movement of the scraper. 105

6. A coke-puller comprising an underworking scraper adapted to operate on its stroke to loosen coke for withdrawal and on its outstroke to withdraw loosened coke, a bar for supporting said scraper provided with a socket at its front end, a sliding extension-plate operative underneath said scraper and provided 110 with a shank extending into said socket, a spring within said socket for thrusting and holding said sliding extension in extended position, and means on said scraper for engaging 115 said extension to withdraw it in extended 120 position in unison with the scraper.

FRANK CHASE SOMES.
